(57) **CLAIM**

We claim the ornamental design for a bus, as shown and described.

DESCRIPTION

FIG. 1 is a front-right-side perspective view of a bus according to a first embodiment;

FIG. 2 is a rear-right-side perspective view of the first embodiment;

FIG. 3 is a front elevation view of the first embodiment;

FIG. 4 is a rear elevation view of the first embodiment;

FIG. 5 is a left-side elevation view of the first embodiment;

FIG. 6 is a right-side elevation view of the first embodiment;

FIG. 7 is a top view of the first embodiment;

FIG. 8 is a front-right-side perspective view of a bus according to a second embodiment;

FIG. 9 is a rear-right-side perspective view of the second embodiment;

FIG. 10 is a front elevation view of the second embodiment;

FIG. 11 is a rear elevation view of the second embodiment;

FIG. 12 is a left-side elevation view of the second embodiment;

FIG. 13 is a right-side elevation view of the second embodiment; and,

FIG. 14 is a top view of the second embodiment.

No claim is made to the bottom view of the bus.

The broken lines illustrate portions of the bus that form no part of the claimed design.

1 Claim, 14 Drawing Sheets
